UNITED STATES PATENT OFFICE.

GEORGE HOWELL THACHER, JR., OF ALBANY, NEW YORK, ASSIGNOR TO FILES
ENGINEERING COMPANY, INC., A CORPORATION OF RHODE ISLAND.

HAND-STOKER.

1,302,453.

Specification of Letters Patent. Patented Apr. 29, 1919.

Application filed September 15, 1917. Serial No. 191,573.

To all whom it may concern:

Be it known that I, GEORGE H. THACHER, Jr., a citizen of the United States, residing at Albany, in the county of Albany, State of New York, have invented certain new and useful Improvements in Hand-Stokers; and I do hereby declare the following to be a full, clear, and exact description of the invention, such as will enable others skilled in the art to which it appertains to make and use the same.

The present invention relates to improvements in hand stokers of the general type in which combustion takes place upon an inclined grate made up of a plurality of transverse grate or stoker bars, with a cleaning or dumping grate bar at the lower end of the incline. In stokers of this general type the stoker bars and the cleaning grate are mounted to rock on inclined supporting bars extending from the front of the furnace to the bridge wall. The stoker bars are usually arranged to form two series of connected bars by attaching alternate bars throughout the length of the grate to actuating mechanism by means of which each series of bars may be rocked independently of the other series to advance the fuel toward the cleaning grate and at the same time sift fine ashes through the stoker bars. In order to prevent fuel falling between the stoker bars as well as to eliminate trouble with clinkers locking the bars when they are oscillated, the bars may be formed on the side toward the upper end of the inclined grate, with curved shields which swing above the plane of the grate when the bars are rocked.

The present invention involves improvements in stoker bars and cleaning grates particularly adapted for use in hand operated stokers of the type described above. In accordance with the present invention the stoker bars are made up of integral shield and end portions and removable grate faces which when in place are supported at one edge by the shield portion of the bar and at the other edge by a rod which at its ends is attached to the end portions of the bar. The shield portion is formed with apertures through which air may be admitted to the fuel while the stoker bar is being manipulated. The bearing members and the lugs by which each bar is connected to the actuating mechanism are formed integral with the end portions of the bar. The entire con-

struction comprises but few parts, which may be quickly and easily assembled, or removed for the purpose of repair or replacement by new ones. The cleaning grate is also of improved shape and construction as particularly adapted for use in combination with the stoker bars of the present invention.

The particular nature of the present invention will appear most clearly from a description of a preferred embodiment thereof as illustrated in the accompanying drawings in which, Figure 1 is a section through a furnace showing the entire stoker in side elevation; Fig. 2 is a transverse section through the stoker along the line 2—2 of Fig. 1, Fig. 3 is a longitudinal section through the cleaning grate and two of the adjacent stoker bars, Fig. 4 is a section through the cleaning grate, along the line 4—4 of Fig. 3, Fig. 5 is a detailed view of a part of the shield and one end of a stoker bar; Fig. 6 is a detailed view of a portion of the grate member of a stoker bar; Fig. 7 is a detailed view of the rod for supporting the grate and Fig. 8 is a detailed view of a portion of a cleaning grate.

Referring to the drawings in which similar reference characters denote similar parts throughout the several views, 10 indicates the front wall of the furnace and 11 the bridge wall thereof. 12 is a casting in the fire door of the front wall and it is provided with a shoulder for supporting the upper ends of inclined bearing bars 13 of which there are three shown in the furnace illustrated herein. Each bearing bar is provided at its lower end with a toe portion 14 which fits on a supporting ledge in the bridge wall. As shown most clearly in Fig. 2, two of the bearing bars are adjacent the side walls of the furnace, while the third bar is placed midway between the other two. The construction thus provides for two inclined grate units, each of which is independent in all respects from the other. It will be understood that by the provision of additional bearing bars, the grate surface of the furnace may be made up of as many units as desired.

Each unit comprises a number of stoker bars 15 extending transversely of the grate and a cleaning grate 16 at the lower end of the inclined grate. The construction of the elements of the stoker bar appears most

clearly from Figs. 5, 6 and 7. Each bar comprises end portions 17 and a shield 18 lying between and preferably formed integrally with the end portions. The shield 5 is provided with a number of air apertures 19, and a row of recesses 20 near its upper edge. Each end portion 17 is provided with an integral hub 21 adapted to fit in correspondingly shaped recesses in the bearing 10 bars. One end portion of each stoker bar has integral extensions forming a pair of lugs 22 which serve as a means for attaching the stoker bar to the actuating mechanism. Each end portion 17 is also provided 15 with a wedge shaped recess 23 and a bolt hole 24. A supporting rod 25 is formed at its ends with wedge shaped extensions 26 adapted to fit within the recesses 23 and provided with bolt holes 27 adapted to register with the bolt holes 24 to receive pins or bolts for holding the supporting rod in place. The grate 28 of each stoker bar is formed of transverse and longitudinal members, the latter being extended as at 29 to 20 form lugs adapted to fit within the recesses 25 20 in the shield of the stoker bar. The other end 30 of each longitudinal member is extended beyond the corresponding transverse member, and preferably curved, thus 30 forming a lower serrated edge which tends to break up the clinkers as they pass between the grates during the cleaning operation. The under face of each longitudinal member is provided near its lower end with a 35 tapering recess 31 adapted to fit over the supporting rod 25, the sides of which should be formed with a corresponding taper.

A portion of a cleaning grate 16 is shown in enlarged view in Fig. 8. It comprises a 40 flat portion 35 provided with the usual longitudinal slots. The grate also has a portion 36 curved upwardly above the plane of the flat portion and this curved portion is provided with a number of air-apertures 37. 45 Extending downwardly from the upper edge of the curved portion 36 is a curved shield portion 38 and these two portions are connected together at the ends of the grate by integral end portions 39, one of which may 50 be extended as at 40 to provide a pair of lugs to which the actuating mechanism may be attached. Hubs 41 for supporting the cleaning grate upon the bearing bars extend outwardly from each end of the grate approxi- 55 mately in line with the point where the flat portion 35 and the curved portion 36 join each other. Along the upper edge of the grate where the curved portion 36 and the shield portion 38 join is a rib or extension 60 42 adapted to engage the serrated lower edge of the adjacent stoker bar to prevent fuel or ashes from falling between the serrations or into the space that would otherwise be left at the upper edge of the clean- 65 ing grate.

As shown most clearly in Fig 1 alternate stoker bars are attached by means of the lugs 22 to a common actuating bar 45 and the other series of stoker bars are attached to a similar actuating bar. Each stoker bar of one series of connected bars is formed with its lugs 22 on the end portions toward one side of the unit, while each stoker bar of the other series of connected bars is formed with its lug 22 on the end portion 70 toward the opposite side of the unit, so that as shown most clearly in Fig. 2 the actuating bars 45 of one series of stoker bars lie on one side of the unit while the corresponding actuating bar for the other series of 75 stoker bars lies on the opposite side of the unit. Thus there is no interference between the actuating bars of each series. Each actuating bar is connected to a rod 46 extending through an aperture in the front 80 wall of the furnace and connected to a lever 47 mounted upon a bracket 48. Each lever is provided with a socket 49 into which may be inserted a hand bar for operating the grate bars. The cleaning grate is rocked by 85 means of a rod 50 connected to the lugs 40 and extending outwardly to the front of the furnace where it may be manipulated by any convenient mechanism. The cleaning grate is so disposed upon the bearing bars 13 90 that its curved shield portion 38 lies closely adjacent the serrated edge of the lowermost stoker bar so that when the cleaning grate is rocked, there will be no loss of fuel between it and the adjacent stoker bar, but on account of the serrated construction of the 95 lower edge of this stoker bar, ashes lying above the same may be discharged when the rib 42 is lifted to uncover this edge. 100

In the operation of the stoker of the present invention, combustion of the fuel takes place primarily upon the stoker bars, but by virtue of the perforated curved portion 36 of the cleaning grate, air will be admitted to the fuel as it passes off of the stoker bars so 105 that any unconsumed fuel which reaches the cleaning grate may be burned while passing over the curved portion 36, and combustion may also take place if any unconsumed fuel reaches the flat portion of the cleaning grate. 110 When it is necessary to shake the grate to move the fuel bed toward the cleaning grate and remove any ashes that may fall through the stoker bars, either one or the other series of stoker bars may be rocked by manipulation of its corresponding lever 47. When 115 any of the bars are rocked into the position shown in Fig. 1, the shields will prevent fuel from dropping between these bars and the bars which have not been moved. This 120 operation will not interfere with the supply of air to the fuel bed since the latter takes place through the apertures 19 in the shields and these apertures should be of sufficient 125 number and extent to permit enough air to 130

pass through the fuel to prevent any appreciable decrease in combustion during the shaking operation.

The two series of connected stoker bars 5 may be operated successively or even simultaneously, if desired. In the latter event, the shield portions of the bars will prevent fuel from falling between the bars even if all of the bars of the grate be tipped. The 10 cleaning grate may be manipulated as desired and whenever it is rocked the shield portion thereof will prevent loss of fuel between this grate and the adjacent stoker bar. By making each stoker bar of the construction 15 described the grate surface thereof may be removed without taking the whole bar out of the furnace. The grate surface may be easily and quickly detached from the stoker bar by simply removing the retaining 20 bolts to permit the supporting rod 25 to be drawn out of the recesses 23 and the lugs 29 of the grate to be drawn out of the recesses 20 in the shield. After this has been done the grate may be lifted off of the supporting 25 rod. The whole construction is of the utmost simplicity, and the component parts of each stoker bar may be assembled without the use of any other pins or bolts save the two which are used for holding the supporting 30 rod in place. By making the stoker bar of separate elements, the casting of the same is simplified and hence the cost of production is lessened.

So far as the improved form of cleaning 35 grate is concerned, it possesses many features of advantage among which may be mentioned the curved portion provided with air apertures over which the fuel passes before reaching the flat surface of the grate 40 and which tends to promote complete combustion of the fuel. The solid shield portion prevents any fuel from falling between this grate and the adjacent stoker bar when the grate is rocked. The weight of the 45 cleaning grate is so distributed upon either side of its bearing hubs that it may be easily rocked even when there is a considerable amount of ash upon its surface.

While the stoker bars and cleaning grates 50 of the present invention have been shown embodied in a particular type of furnace, it will be understood that they are equally applicable to furnaces of other types, and also that various changes may be made in the 55 details of construction of all of the members without departing from the principle of the invention.

I claim:

1. A hand stoker having inclined bearing 60 bars and a plurality of stoker bars mounted to rock on the bearing bars, each of said stoker bars being provided with a removable grate and a curved shield on the side of the bar toward the upper end of the stoker, the 65 shield being adapted to swing above the upper face of the stoker when the bar is tipped and being provided with apertures through which air may be supplied to the fuel bed when the stoker bar is in tipped 70 position.

2. A hand stoker having inclined bearing bars and a plurality of stoker bars mounted to rock on the bearing bars, each of said stoker bars being provided with a flat removable grate and a curved shield on the 75 side of the bar toward the upper end of the stoker, the shield being adapted to swing above the upper face of the stoker when the bar is tipped and being provided with apertures through which air may be supplied to 80 the fuel bed when the stoker bar is in tipped position.

3. A hand stoker having inclined bearing bars and a plurality of stoker bars mounted to rock on the bearing bars, each of said 85 stoker bars being provided with a flat removable grate and a curved shield on the side of the bar toward the upper end of the stoker, the shield being adapted to swing above the upper face of the stoker when the bar is 90 tipped and being provided with apertures through which air may be supplied to the fuel bed when the stoker bar is in tipped position and a rocking cleaning grate mounted at the lower ends of the bearing bars. 95

4. A hand stoker having inclined bearing bars and a plurality of stoker bars mounted to rock on the bearing bars, each of said stoker bars being provided with a flat removable grate and a curved shield on the side 100 of the bar toward the upper end of the stoker, the shield being adapted to swing above the upper face of the stoker when the bar is tipped and being provided with apertures through which air may be supplied to 105 the fuel bed when the stoker bar is in tipped position and a rocking cleaning grate mounted at the lower ends of the bearing bars, said cleaning grate being provided with a curved shield adjacent the lowermost 110 stoker bar to prevent loss of fuel when the cleaning grate is tipped.

5. A hand stoker having inclined bearing bars and a plurality of stoker bars mounted to rock on the bearing bars, each of said 115 stoker bars being provided with a removable grate and a curved shield on the side of the bar toward the upper end of the stoker, the shield being adapted to swing above the upper face of the stoker when the bar is tipped and being provided with apertures through which air may be supplied to 120 the fuel bed when the stoker bar is in tipped position and a rocking cleaning grate mounted at the lower ends of the bearing bars, said cleaning grate being provided with a flat slotted grate surface, a curved portion provided with apertures through which air may be admitted to the fuel upon the grate and a downwardly extending curved shield lying 125 130

adjacent the lowermost stoker bar to prevent loss of fuel when the cleaning grate is tipped.

6. In stoking bars for furnaces, the combination of integral shield and end portions, a removable grate and means whereby the grate may be supported upon the end and shield portions.

7. In stoking bars for furnaces, the combination of a curved shield portion provided with air apertures and recesses and end portions integral with the shield portion, a supporting rod detachably mounted upon the end portions and a grate supported upon the rod and having lugs adapted to enter the recesses in the shield.

8. In stoking bars for furnaces, the combination of a curved shield portion provided with air apertures and recesses, end portions integral with the shield portion and provided with bearing hubs and downwardly extending lugs, a removable grate and means whereby the grate may be supported upon the end and shield portions.

9. In stoking bars for furnaces, the combination of a curved shield portion provided with air apertures and recesses, end portions integral with the shield portions and having wedge-shaped recesses on their inner faces, a supporting rod provided with wedge-shaped extensions adapted to fit the said recesses, means passing through the extensions and the said end portions to hold the rod in place and a grate supported upon the rod and having lugs adapted to enter the recesses in the shield portion.

10. In stoking bars for furnaces, the combination of a curved shield portion provided with air apertures and recesses, end portions integral with the shield portion and provided with bearing members and downwardly extending lugs and being formed with wedge-shaped recesses on their inner faces, a supporting rod provided at its ends with wedge-shaped extensions adapted to enter the said recesses, means passing through the said extensions and the said end portions for holding the rod in place, and a flat grate having lugs adapted to enter the recesses in the shield portion and having recesses adapted to fit over the top of the supporting rod.

11. In combination, a cleaning grate for furnaces comprising a flat slotted grate, an

integral curved portion extending above the flat surface and provided with air apertures, a curved shield extending downwardly from the upper edge of the curved portion and a rib extending along the meeting edge of the shield and the curved portion, and a stoker bar having a movable serrated edge adjacent to said curved shield; substantially as described.

12. A hand stoker having inclined bearing bars, a plurality of stoker bars mounted to rock on the bearing bars, and each provided with a serrated lower edge, and a cleaning grate mounted to rock on the lower ends of the bearing bars, said cleaning grate being provided with a flat portion having apertures therein, a portion forming an integral upwardly curved extension of said flat portion, a curved shield portion integral with and extending downwardly from the upper edge of the curved extension and pivot members projecting from the sides of the grate at substantially the intersection of the flat portion and the curved extension, said pivot members being so placed on said bearing bars that the curved shield portion lies closely adjacent the serrated edge of the lowermost stoker bar in order to prevent loss of fuel when the cleaning grate is rotated about said pivots.

13. A hand stoker having inclined bearing bars, a plurality of stoker bars mounted to rock on the bearing bars, and each provided with a serrated lower edge, and a cleaning grate mounted to rock on the lower ends of the bearing bars, said cleaning grate being provided with a flat portion having apertures therein, a portion forming an integral upwardly curved extension of said flat portion, pivot members projecting from the sides of the grate at substantially the intersection of the flat portion and the curved extension and a shield portion integral with and extending downwardly from the edge of the curved extension and curved concentrically about said pivot members as a center, said pivot members being so mounted on the bearing bars that the said shield portion lies closely adjacent the serrated edge of the lowermost stoking bar to prevent loss of fuel when the cleaning grate is rotated on the pivot members.

In testimony whereof I affix my signature.

GEORGE HOWELL THACHER, Jr.

It is hereby certified that the name of the patentee in Letters Patent No. 1,302,453, granted April 29, 1919, for an improvement in "Hand-Stokers," was erroneously written and printed as "George Howell Thacher, Jr.," whereas said name should have been written and printed as *George Hornell Thacher, Jr.*; and the said Letters Patent should be read with this correction therein that the same may conform to the record of the case in the Patent Office.

Signed and sealed this 22d day of July, A. D., 1919.

[SEAL.]

R. F. WHITEHEAD,

Acting Commissioner of Patents.

Cl. 110—39
